UNITED STATES PATENT OFFICE.

EWALD HANUS, OF TEGEL, NEAR BERLIN, GERMANY.

BALL-GRINDING MACHINE.

REISSUED

1,205,531.

Specification of Letters Patent. Patented Nov. 21, 1916.

Application filed September 8, 1916. Serial No. 119,008.

To all whom it may concern:

Be it known that I, EWALD HANUS, engineer, subject of the King of Prussia, residing at No. 14 Treskowstrasse, Tegel, near Berlin, Germany, have invented certain new and useful Improvements in Ball-Grinding Machines, of which the following is a specification.

The present invention relates to an improvement in ball grinding machines of the type described in my United States Letters Patent No. 1,124,018, in which machines there is interposed between two plates formed with annular grooves, a third or 15 central plate having grooves on both sides thereof, this third plate being mounted stationarily and being formed with an axial charging recess extending entirely through the plate. In the constructional form of the 20 machine disclosed in the said patent this central plate consists of two symmetrically arranged separate plates which are held together by means of a casing section specially formed for that purpose.

For a ball grinding machine of the design described to work satisfactorily it is necessary that the operating parts, and in particular the plates, are machined absolutely concentrically, and also that they have been 30 assembled absolutely concentrically. It is, obviously, very difficult to meet both these conditions, and it is, in particular, difficult, to machine the plates and their grooves on a lathe so accurately that they run absolutely 35 true relatively to each other. Furthermore the absolute correspondence between the grooves will be easily disturbed by slight displacements from the center caused in assembling. The smallest inaccuracy in this 40 regard will, however, have a great detrimental effect on the accurate shape of the balls ground, inasmuch as plates which are not absolutely concentric, cannot possibly produce, when worn, an absolutely spherical 45 form of ball.

It is the object of the present invention to obviate this difficulty, and to effect this the two separate plates composing the central grinding plate are made in such a manner that they may adjust themselves both radially and axially in accordance with any possible inaccuracies in the concentricity of the grooves. By such arrangement the accurate working of the machine, and in particular the absolutely true and spherical shape of the balls ground thereon are in-

sured, as the plates with their grooves will automatically assume the correct operating position, even in case they are not accurately machined or not accurately assembled. 60

In the accompanying drawing the present invention is exemplified in a constructional form.

Figure 1 is a view of the machine, partly in vertical cross section and partly in elevation; Fig. 2 is a side elevation with the adjacent grooved plate partly broken away.

The essential feature of the construction shown is that the two separate plate sections *a* and *b* are not dependent for their arrangement upon the use of a casing cover, which latter in this instance may be dispensed with, but are disposed on opposite sides of a rigid partition *s* and are supported at their lowest point in such a manner that 75 they can, on the one hand, oscillate slightly in a radial direction, and therefore adjust themselves absolutely concentrically, and, on the other hand, shift axially, as far as this may become necessary. To provide for 80 this, a bar *w*, rounded on its upper side, is arranged transversely of the machine at the bottom of the semi-cylindrical casing section *r*, so as to serve as a support for the said plates *a*, *b*, and these plates which are 85 fitted loosely into the casing are recessed at *w* (Fig. 1) so as to rest on said bar *w* in such a way that they can rock like a pendulum thereon, said plates having a certain amount of play as indicated at *y* to 90 permit such rocking movement.

The partition *s* is preferably made in one piece with the casing section *r*, and is formed with holes *t* close to its periphery, which holes are adapted to receive springs *u*. 95 These springs are introduced under tension and bear at their ends against the plates *a* and *b*, respectively, so that the said plates are yieldingly held against the rotating outer plates. For checking the radial oscillations flat springs may be provided at the upper edges *x*, *x'* of the casing, which springs will bear against the periphery of the plates *a*, *b* and tend to overcome the jerky sidewise oscillations of said plates. 100 105

The machine is provided with a charging hopper *d*, which is constituted by a recess or opening having a gable-shaped bottom, as in my earlier or patented construction, this opening or recess extending through 110 the two plates *a* and *b* and the partition *s*, as shown.

I claim:

1. In a ball-grinding machine, the combination of a pair of rotatable grinding plates arranged in spaced, parallel relation to each other and having their inner faces formed with annular grooves; a pair of relatively stationary grinding plates fitting loosely in the space between the rotatable plates, and likewise arranged in spaced, parallel relation to each other, said stationary plates having their outer faces formed with annular grooves registering with the first-named grooves; a stationary partition plate fitting in the space between the stationary grinding plates; and resilient means for pressing said stationary plates against said rotatable grinding plates.
2. In a ball-grinding machine, the combination of a pair of grinding plates arranged in spaced, parallel relation to each other and having their inner faces formed with annular grooves; a pair of relatively stationary grinding plates fitting loosely in the space between the rotatable plates, and likewise arranged in spaced, parallel relation to each other, said stationary plates having their outer faces formed with annular grooves registering with the first-named grooves; a stationary partition plate fitting within the space between the stationary grinding plates, and formed with a plurality of transverse, opened, apertures; and springs disposed in the said apertures and bearing at opposite ends against the inner faces of said stationary grinding plates, to yieldingly press the latter against said rotatable grinding plates.
3. In a ball-grinding machine, the combination of a pair of rotatable grinding plates arranged in spaced, parallel relation to each other and having their inner faces formed with annular grooves; a pair of relatively stationary grinding plates fitting loosely in the space between the rotatable plates, and likewise arranged in spaced, parallel relation to each other, said stationary plates having their outer faces formed with annular grooves registering with the first-named grooves; a stationary partition plate fitting in the space between the stationary grinding plates; and resilient means for pressing said stationary grinding plates against said rotatable grinding plates; said machine having a charging recess which is formed jointly in said stationary grinding plates and said partition plates and which has a width equal to the combined thickness of said plates.
4. In a ball-grinding machine, the combination of a pair of rotatable grinding plates arranged in spaced, parallel relation to each other and having their inner faces formed with annular grooves; and a relatively-stationary grinding plate fitting in the space between said rotatable plates and comprising

a pair of counter-part plate-like members having a limited yielding movement both axially and radially; said members having their outer faces formed with annular grooves registering with the first-named 70 grooves.

5. In a ball-grinding machine, the combination of a pair of rotatable grinding plates arranged in spaced, parallel relation to each other and having their inner faces formed with annular grooves; a pair of relatively-stationary grinding plates fitting loosely in the space between the rotatable grinding plates and likewise arranged in spaced, parallel relation to each other; said stationary grinding plates having their outer faces formed with annular grooves registering with the first-named grooves, and also having a limited yielding movement both axially and radially; and a stationary partition plate fitting in the space between the stationary grinding plates.

6. In a ball-grinding machine, the combination of a pair of rotatable grinding plates arranged in spaced, parallel relation to each other; a pair of relatively-stationary grinding plates interposed between the rotatable grinding plates; and a bearing member on which the stationary grinding plates rest at their lower portions, and about which they are adapted to rock.

7. In a ball-grinding machine, the combination of a pair of rotatable grinding plates arranged in spaced, parallel relation to each other; a pair of relatively-stationary grinding plates interposed between the rotatable grinding plates and provided with peripheral recesses at their bottom portions; and a transversely-arranged bar fitting in said recesses and constituting a bearing 100 about which said stationary grinding plates are adapted to rock.

8. In a ball-grinding machine, the combination of a pair of rotatable grinding plates arranged in spaced, parallel relation to each other; a pair of relatively-stationary grinding plates interposed between the rotatable grinding plates and likewise arranged in spaced, parallel relation to each other; a stationary partition plate fitting in the space 110 between said stationary grinding plates; and a bearing member on which the stationary grinding plates rest at their lower portions, and about which they are adapted to rock, said bearing member disposed beneath 115 said partition plate and extending on opposite sides thereof.

9. In a ball-grinding machine, the combination of a pair of rotatable grinding plates arranged in spaced, parallel relation to each other; a pair of relatively-stationary grinding plates interposed between the rotatable grinding plates; resilient means for pressing said stationary grinding plates against 125 said rotatable grinding plates; and a bear- 130

ing member on which the stationary grinding plates rest at their lower portions and about which they are adapted to rock.

10. In a ball-grinding machine, the combination of a pair of rotatable grinding plates arranged in spaced, parallel relation to each other; a pair of relatively-stationary grinding plates interposed between the rotatable grinding plates and provided with 10 a plurality of transverse, open-ended apertures; springs disposed in said apertures and bearing at opposite ends against the inner faces of said stationary grinding plates, to yieldingly press the latter against the rotatable grinding plates; and a bearing member on which the stationary grinding plates rest at their lower portions, and about which they are adapted to rock.

11. In a ball-grinding machine, the combination of a pair of rotatable grinding plates arranged in spaced, parallel relation to each other and having their inner faces formed with annular grooves; a pair of relatively-stationary grinding plates 25 fitting in the space between the rotatable grinding plates and having their outer faces formed with annular grooves registering with the first-named grooves; and resilient means interposed between the stationary plates for yieldingly pressing them laterally against said rotatable grinding plates.

12. In a ball-grinding machine, the combination of a pair of rotatable grinding plates arranged in spaced, parallel relation

to each other and having their inner faces 35 formed with annular grooves; a pair of relatively-stationary grinding plates fitting in the space between the rotatable grinding plates and having their outer faces formed with annular grooves registering with the 40 first-named grooves; resilient means interposed between the stationary plates for yieldingly pressing them laterally against said rotatable grinding plates; and a bearing member upon which said stationary grinding plates rest at their lower portions, and about which they are adapted to rock. 45

13. In a ball-grinding machine, the combination of a pair of rotatable grinding plates arranged in spaced, parallel relation 50 to each other; a pair of relatively-stationary grinding plates interposed between the rotatable grinding plates and provided with transverse peripheral recesses at their bottom portions; a transversely-disposed bar 55 fitting in said recesses and constituting a bearing about which said stationary grinding plates are adapted to rock; and resilient means interposed between the stationary grinding plates for yieldingly pressing them laterally against said rotatable grinding plates. 60

In testimony wherof I affix my signature.

EWALD HANUS.
